UNITED STATES PATENT OFFICE.

E ROY ALLING, OF SODUS, NEW YORK.

LABELING-MACHINE.

1,284,547.

Specification of Letters Patent. Patented Nov. 12, 1918.

Application filed October 31, 1917. Serial No. 199,464.

To all whom it may concern:

Be it known that I, E ROY ALLING, a citizen of the United States, and resident of Sodus, in the county of Wayne and State 5 of New York, have invented a new and Improved Labeling-Machine, of which the following is a full, clear, and exact description.

This invention relates to labeling machines and has particular reference to such 10 devices designed for the application of wrappers or labels to fruit cans or the like.

Among the objects of the invention is to provide improved means for controlling a stack of labels in such a manner that they 15 will be delivered singly in succession to the individual cans as the latter are rolled over said stack of labels.

Another object of the invention is to provide improved facilities for supplying a 20 quantity of paste to one end of the labels, namely that end which is applied last and to overlap the other portion of the label after wrapping around the can.

With the foregoing and other objects in 25 view the invention consists in the arrangement and combination of parts hereinafter described and claimed, and while the invention is not restricted to the exact details of construction disclosed or suggested herein, 30 still for the purpose of illustrating a practical embodiment thereof reference is had to the accompanying drawings, in which like reference characters designate the same parts in the several views, and in which—

35 Figure 1 is a vertical longitudinal section of a preferred embodiment of the invention showing the relation of the paste applying and holding devices to the pile or stack of labels supported upon the bed of the ma- 40 chine.

Fig. 2 is a side elevation of a part of the mechanism shown in Fig. 1.

Fig. 3 is a vertical transverse section on the line 3—3 of Fig. 1.

45 Fig. 4 is a sectional view on the line 4—4 of Fig. 2; and

Fig. 5 is a bottom plan view of the paste spreader.

Referring now more particularly to the 50 drawings wherein is shown a more or less diagrammatic representation of my improvements. 10 indicates a receptacle adapted to hold a suitable quantity of paste adapted to be delivered by gravity or the like through a flexible tube 11 into and through the mouth portion 12 of a paste

spreading device 13. The receptacle 10 is supported in any suitable manner as by means of a bracket 14 on or at one side of one of the runways 15 of the machine. 60 Either or both of the runways may be provided with a slot 16 formed in the vertical part of the runway through which the flexible tube 11 extends.

The spreader 13 comprises a rectangular 65 box like structure of a length sufficient to reach substantially across from one runway to another transversely of the machine. The spreader is provided with a removable cover 17 having lugs fitted into the upper edge of 70 one side and having a spring hasp along its other edge coöperating with the upper edge of the opposite side, the purpose of the cover being to facilitate the cleansing of the device or other purposes. The bottom of 75 the spreader comprises a pair of bars 18 and 19 extending parallel to each other along the lower edges of the two sides of the device and having a length providing for an extension of the same at each end of the 80 receptacle; they also extend laterally somewhat beyond the bottom of the paste spreader or receptacle 13 to provide ample stability for the same. The inner edges of the bars are provided with grooves 20 lying 85 in the same plane and along which the bottom closure members 21 of the paste spreader are adapted to slide. (See Figs. 4 and 5.) These closure members 21 are shown as of equal length and each is pro- 90 vided with a finger piece 22 to be grasped between the projecting ends of the bars 18 and 19 for the purpose of drawing out or opening the closure members to permit the paste to be delivered through the bottom of 95 the spreader.

The spreader 13 is supported resiliently between the runways, as for example, by a pair of leaf springs 23 and 24 coöperating with each end of the spreader. These 100 springs are attached in any suitable manner beneath the runways, and are adjusted as to their tension by set screws 25 or the like. Each spring 23 has its free end projected downwardly into a slot 26 in the end of the 105 bar 18 whereby these springs 23 serve two functions, mainly to bear downwardly upon the ends of the bar and also prevent forward or rearward movement thereof with respect to the anchorage for the springs. The other 110 springs 24 bear downwardly only upon the rear bar 19.

27 indicates a pile or stack of labels supported upon a bed plate 28, which in turn is resiliently supported upon pedestal 29 extending downwardly from the cross braces 30 and 31 and around which are secured cushioning devices such as coil springs 32. These labels, it will be understood, are placed face downward and the stack is so disposed that the rear end of the labels is disposed directly beneath the paste spreader 13. Among the important novel features of this invention may be noted one or more hooks 33 fixed in any suitable position as on the lower edge of the cross brace 30 and having a sharp point projecting into the front or upper end of the uppermost label. If only one hook is used it would preferably be disposed at the center of the end of the pile whereby when the can is brought down upon this end of the label to paste the labels the corners or points of the label will readily coil upward to facilitate the application thereof to the curved surface of the can already supplied with the paste along one side from any suitable source well known in the art. At the other end of the pile of labels is another important feature consisting of one or more knifelike points 34 each carried in a socket 35 adjustably connected to the cross brace 31. By providing a sharp cutting point there is no likelihood of any obstruction taking place due to the tearing out of a bit of the label when the label is drawn beneath the paste spreader in making the final application to the can.

It will be understood that the paste from the spreader 13 will be applied only to the lower end of the label and to facilitate this application the bar 18 is provided with a

series of closely related grooves or scores 18' 40 adjacent to the label. This feature insures that a sufficient quantity of the paste will be delivered to the label while the label is being drawn from beneath the spreader. While the labels are thus being delivered singly 45 from the top of the pile or stack 27, such stack will be elevated automatically by virtue of the springs 32 acting upon the bed plate.

I claim:

1. In a labeling machine the combination with a paste spreader having an open bottom and means to support a pile of labels with one end directly beneath and in communication with said open bottom, of temporary 55 means for holding down the free ends of the labels remote from the spreader and a knife pointed device coöperating with the ends of the labels adjacent to the spreader to hold the same to permit the withdrawal of the 60 uppermost label beneath said open bottom.

2. In a labeling machine, a paste spreader comprising a box-like structure having an open bottom, said opening being provided on two sides by a pair of bars projecting beyond 65 the ends of the spreader, closure means for the bottom of the spreader held in place by the said bars, and a plurality of springs having one end of each fixed and the other end of each coöperating with an end of one of 70 said bars, said springs serving to tend to hold the spreader down, and some of said springs serving to hold the spreader from lateral movement.

E. ROY ALLING.
